18 Claims. (Cl. 91—401)

This invention relates generally to cryogenic apparatus and more particularly is concerned with such apparatus using a piston reciprocating in a suitable cylinder, there being annular grooves provided on the bearing surfaces of the piston or cylinder and gas under high pressure flowing in the clearance space between the piston and cylinder.

In cryogenic apparatus of the character with which this invention is concerned, a working gas is expanded approximately adiabatically from high to low pressure by producing mechanical work, the gas being thereby cooled. Such apparatus are of two types, namely, expansion turbines and expansion piston machines, both being used to produce low temperatures, particularly in the liquefying of gases which have low boiling points, and without pre-cooling through the use of other liquefied gases having higher boiling points. Examples of such gases which require cooling for liquefying are neon, hydrogen and helium. Since expansion turbines can generally effectively process large quantities of gas and low pressure ratios, only expansion machines of the reciprocating piston type are used for medium to small liquefying and gas cooling installations.

In known piston type cryogenic machines the working piston is provided with annular grooves on its surface and the clearance volume between the piston and the cylinder surface is of right cylindrical configuration, that is, the juxtaposed surfaces are co-parallel with the theoretical distance between them parallel throughout. This clearance volume in prior devices has not been of equal dimension on opposite sides of the piston, as will be seen. The clearance volume will hereinafter be called the space between the piston and the inner cylinder surface. In the prior structures, the annular grooves had two function, one—to improve the pressure seal of the working chamber from the outer chamber, and, two—to equalize the pressure around the circumference of the piston. These prior devices did not achieve a contact-free or "floating" stroke of the piston.

Because of the inability to achieve true floating stroke, prior cryogenic apparatus of the piston type could be operated only at low speeds, and even then wear on the bearing surfaces was unavoidable.

In addition to the above disadvantages, in prior devices introduction and expulsion of the gas was achieved through the use of mechanically or electromagnetically operated valve mechanisms. These mechanisms represent additional structural parts, complicate the construction of the machine and impair its safety. In cases where the working gas could not be permitted to come in contact with lubricating medium or in the production of very low temperatures where the use of oil lubrication is not feasible for physical reasons, a fully floating piston stroke has not been possible in any prior apparatus of which we are aware.

The invention herein has as its most important objects the elimination of the above disadvantages and the provision of a piston type cryogenic apparatus in which the piston reciprocates in a fully floating condition without contacting the surfaces of the cylinder so that the piston may be operated at high speed and without substantially any wear on the moving parts thereof.

2

Still a further object of the invention is to provide a piston type cryogenic apparatus in which the construction and control thereof are considerably simplified over prior devices through the elimination of valve mechanisms 5 having moving parts.

Another object of the invention is to provide apparatus of the character described in which a floating stroke of the piston is achieved by means of gas lubrication, there being a plurality of annular grooves along the 10 length of the working surface of the piston or the cylinder, and the grooves being of such axial distance apart and the clearance space between the piston and wall being of such configuration as to achieve the desired floating effect, irrespective of the direction of flow of the 15 gas.

Still another object of the invention is to provide a piston type cryogenic apparatus in which the valve gear is eliminated by providing suitable inlet and outlet chambers in the cylinder itself and means in the piston for 20 operating the same for achieving the introduction, expansion and expulsion of the gas.

According to the invention, the piston or the cylinder of the apparatus is provided on its walls with fine annular grooves spaced along the length of the working surface, 25 the axial distance between adjacent grooves being between $\frac{1}{20}$ and $\frac{1}{100}$ the circumference of the piston, and the surface of the piston or cylinder is so formed that the radial clearance space varies, being different dimensions 30 axially along the length of the piston between any two adjacent grooves.

The invention is further characterized by the provision of means in the piston itself to enable the same to function as a control valve, inlet and outlet ports and chambers being formed in the bearing surface of the cylinder.

Other objects and advantages of the invention will appear from the description of preferred embodiments which follow in connection with the drawings which illustrate the same. The same characters of reference are used throughout the several figures of the drawings 40 to illustrate the same or equivalent parts wherever feasible.

In the said drawings:

FIG. 1 is a fragmentary diagrammatic view on a greatly exaggerated scale showing one side of the radial 45 clearance space between a piston and cylinder constructed in accordance with the invention.

FIG. 2 is a pressure diagram illustrating the flow conditions in the clearance space of FIG. 1, the principal points of pressure being aligned for discussion.

FIG. 3 is a fragmentary schematic and diagrammatic view of a piston and cylinder constructed in accordance with the invention, specifically the structure of FIG. 1.

FIG. 4 is a view similar to that of FIG. 3, but illustrating a modified form of the invention.

FIG. 5 is a pressure diagram similar to that of FIG. 2 but related in this case to the construction of FIG. 4.

FIG. 6 is a schematic vertical sectional view through a cylinder and piston unit of a cryogenic machine constructed in accordance with the invention, the grooves and clearance space not being shown in this view because of the practical problems of illustrating the same.

FIG. 7 is a schematic vertical sectional view through a modified form of cylinder and piston unit.

FIG. 8 is a fragmentary schematic vertical sectional view of a modified form of the invention in which there is an adjustable bottom plug in the cylinder.

FIG. 9 is a chart illustrating the relative values of pressure and volume in the working cycle of the apparatus of the invention.

Referring now to the drawings, in FIG. 1 a fragment is shown of a piston and cylinder unit constructed in ac-

cordance with the invention, the view being sectional and taken at one side of the piston. It will be appreciated that the dimensions are greatly exaggerated to aid in the explanation, since the radial distance between the piston and the cylinder wall is a few microns. The cylinder is designated 1, the piston 2, and 3 and 4 are two successive annular grooves. The direction of flow of the gas is designated by the arrow and the space between the piston and inner surface of the cylinder is designated s . Note that this space varies substantially uniformly, decreasing in the direction of flow, so that there is a change in pressure along the length of the piston. This arrangement of decrease in clearance space may be provided overall or part of the piston (or the cylinder surface).

The gas pressure p' in the annular groove 3 is higher than the gas pressure p'' in the annular groove 4.

For dimensions encountered, where, as stated, the dimension s is a few microns, as necessary in the practical devices, the flow of gas through the clearance space has approximately the same action as the viscous flow of a compressible medium in the isothermal case. (Viscous in this case means that only the frictional forces are taken into consideration to the exclusion of forces due to inertia. Compressible and isothermal means that the gas expands while flowing through the clearance space but does not cool because of thermal contact with the walls.)

The mathematical treatment of this type of flow, considering the case of a constant dimension s , for a pressure distribution from p' to p'' for any length l becomes:

$$p^2 = p'^2 - (p'^2 - p''^2)l/L$$

which is recognized as a quadratic equation, indicated in FIG. 2 by the dashed line curve. As Equation 1 shows, the pressure distribution between two annular grooves in the case of a clearance space which is uniform, i.e., parallel, does not depend upon the radial distance of the space itself, so long as the latter remains so small that the conditions under which Equation 1 has been derived are met.

For the case that the clearance space s decreases in radial dimension in the direction of flow of the gas, the calculation yields a pressure distribution which corresponds qualitatively to the solid line curve of FIG. 2. This can readily be seen if it is considered that the throttling of the gas and the pressure gradient must be greater at the points of smaller clearance than larger. There is therefore a low pressure drop in the annular groove 3, and with decreasing clearance dimension toward the annular groove 4, an increasingly greater pressure drop, so that the solid curve must always be above the dashed line curve.

An important feature of the invention, and one which makes the floating action possible without contact between the walls of cylinder and the piston surface is that the piston is always self-centering in the cylinder. If it moves out of perfect concentricity it is in an unstable condition, and forces produced tend to move it into perfect centering, at which position it will reciprocate in a stable condition. FIG. 3 shows in exaggerated schematic diagram, a piston 2 constructed according to the invention and having the annular grooves 3, 4, 5, 6 . . . and throttling clearance spaces between the annular grooves whose radial dimension decreases in the direction of gas flow. A stabilizing effect by the gas flowing in the clearance space is achieved to provide the self-centering action described in the following manner:

With an eccentric displacement of the piston in the cylinder for example, to the left as shown in FIG. 3, different conditions arise on the right and left for the variation of the radial clearance dimension in an axial direction relative to the clearance dimension itself. On the side of the piston which has the larger radial clearance dimension, the relative variation of the clearance distance in an axial direction is small and the pressure distribution is similar to that in the so-called parallel situation discussed above in connection with the dashed

line curve of FIG. 2. This condition is approached closer with an increase in the clearance dimension. On the opposite side of the piston, however, the clearance dimension is much narrower, and the relative variation in an axial dimension consequently is much greater.

The pressure distribution on the narrow clearance side of the piston will be substantially different, therefore, than on the wider clearance side, considering of course the distribution along the axial length of the piston between annular grooves. This difference will increase as the piston and cylinder approach one another on the narrow side, and the distribution is like the solid line curve of FIG. 2. Because of this, there is a higher mean static gas pressure on the narrow clearance side than there is on the wider clearance side, and consequently a resultant force is exerted by the gas which tends to force the piston into a perfectly concentric position within the cylinder. The mean static gas pressure is expressed as follows:

$$\bar{p} = \frac{l}{L} \int_0^L p(l) dl$$

The annular grooves on the piston circumference have the function of maintaining the same outlet and end pressure at all points of the circumference for gas flow in the wedge shaped clearance space between grooves.

The foregoing consideration provides an indication of the optimum axial distance between adjacent grooves. Principally, the different pressure distribution around the circumference of the piston when eccentric can be equalized by the flow of gas around the piston. A sufficiently close spacing of the grooves may result in the creation of a greater resistance to flow in the clearance space along the circumference than the flow from groove to groove.

The gas under these circumstances would flow mainly in an axial direction between the annular grooves and the tangential or circumferential flow would be of little substantial consequence. As an optimum interval between annular grooves to give the best results we have found that this distance should be between $\frac{1}{20}$ and $\frac{1}{100}$ of the piston circumference. The foregoing considerations apply strictly speaking only to the piston when at rest in the cylinder, but since the piston velocities occurring in practice are much lower than the gas velocity in the clearance space, the determination is a good approximation even for a moving piston.

Stabilization or self-centering by gas pressure occurs for the construction of FIG. 3 when the gas flows in the direction indicated. Self-centering of the piston in the cylinder can be achieved by a different arrangement in which the clearance space between a pair of adjacent grooves varies in radial dimension by having a minimum dimension at the groove edges and a maximum dimension half way between them. Such an arrangement is shown schematically in FIG. 4. In this view, the piston 2 is arranged to reciprocate in the cylinder 1, two grooves 3 and 4 being shown in the piston. The radial dimension s is maximum at 7 between the grooves, and minimum at the groove edges. In this arrangement, contrary to the action of the structure of FIGS. 1 to 3, the self-centering action of the piston due to gas pressure differential on opposite sides of the piston, does not depend upon the direction of flow of the gas in the clearance space.

FIG. 5 is a chart showing qualitatively the pressure distribution along the axial length of the clearance space for the flow in the direction of increasing l (from the bottom to the top). The dashed line curve represents the pressure distribution for a clearance space of uniform, that is, parallel, radial dimension. The solid line curve represents qualitatively the pressure distribution for the profile shown in FIG. 4. The explanation of this curve is as follows: At the start (bottom) there is a great pressure drop due to the narrow clearance dimension at this point, followed by a region of relatively low pressure

drop because of the wide clearance dimension, and finally another high pressure drop at the end because of the narrow radial clearance dimension. An analysis of this arrangement shows that with a symmetrical profile, that is with similar variation in clearance dimension on both sides of the line of symmetry S , the intersection of the solid line pressure curve with the dashed line lies likewise on S . This indicates clearly that the mean static pressure $\bar{p}$, which corresponds to the solid line curve, is greater than that corresponding to the dashed line curve. Thus, on the basis of the explanation of FIG. 3, there will be a stabilizing or self-centering effect upon the piston in the clearance space due to gas pressure.

In FIGS. 6 to 8, there are illustrated diagrammatic views of piston type cryogenic machines constructed in accordance with the invention as described above, but including additional novel features which result in simple and highly efficient apparatus. There is a cylinder 10 with a reciprocating piston 11 arranged to move therein and perform work during the expansion of the working gas. The piston is preferably coupled with a connecting rod 12 which can perform the work upon some external instrumentality (not shown). The cylinder and piston 11 define the chamber 13 which will be filled by the incoming gas.

The cylinder 10, according to the invention, is provided in the axial range of the stroke of the piston, with an annular groove 14 connected by several radial passageways 15 circumferentially spaced about the cylinder with an annular enclosed gallery 16 connected to a high pressure source of the working gas (not illustrated) through a conduit 17. Adjacent lower dead center of the piston movement an annular groove 18 is formed in the piston connected by radially and downwardly extending channels 19 spaced circumferentially about the piston to a central axially extending bore 20. When this groove 18 passes over the annular groove 14 in downward movement of the piston 11, the chamber 13 will receive a charge of the working gas at a pressure p_1 . When the piston 11 rises, the groove 18 passes over and above the groove 14 so that the gas is cut off from entering further, and the charge is complete. The gas in the chamber 13 now expands and performs work through the connecting rod 12, the equivalent of which is withdrawn in the form of heat from the working gas, thereby cooling the gas.

At the end of the expansion of the gas, when the piston is in the vicinity of its upper dead center, the bottom end 21 of the piston uncovers an annular groove 22 formed in the cylinder wall, and the expanded, cooled gas escapes through a plurality of radial passageways 23 into the annular gallery 24 and thence passes by way of the conduit 25 to the means for re-cycling the gas (not shown). The ratio of incoming charge volume to terminal volume is chosen so that the pressure p_2 in the chamber 13 is greater at the end of the expansion portion of the cycle than the counter pressure p_3 in the exhaust gas line 25. When the piston 11 descends, the outlet channel groove 22 is again closed and the working gas in the chamber 13 is recompressed from p_3 to p_4 . Since p_3 is lower than p_2 , same volume ratio exists in the recompression as in expansion and p_4 is less than the inlet pressure p_1 so that after the inlet channel has been uncovered the chamber 13 can be charged once more. The pressure and volume values for this working cycle can be taken from the diagram represented in FIG. 9. V_f and V_e correspond to the initial and terminal volumes.

There is always a pressure gradient between the annular grooves 14 and 22 which is defined as p_1-p_3 and consequently gas flows constantly between the piston and bearing surface of the cylinder, which effects the so-called gas lubrication of the moving piston and keeps it floating within the cylinder out of contact with the surface thereof, this being due to the construction described in connection with FIG. 4.

The central axial bore 20 is advantageous in that the piston 11 is interiorly scavenged by cold gas. This is important during the cooling period, since the coefficient of expansion of the piston and cylinder are relatively great in the range of room temperature, so that it is essential that they both cool simultaneously. If this were not achieved, the cylinder would cool faster than the piston and contract to seize the piston.

In the embodiment of FIG. 7 the discharge of the gas is not controlled by the bottom end 21 of the piston but by the annular groove 18, the latter also being used for charging the chamber 13. The expanded gas is released by the coincidence of the groove 18 with the annular groove 22 in the upper part of the cylinder, this cycle also corresponding to the diagram of FIG. 9. Otherwise, the construction is similar to that of FIG. 6.

Regulation of the intake and exhaust volume ratio can be effected by the arrangement shown in FIG. 8. Instead of a fixed bottom wall in the cylinder 10, according to FIG. 6, there is a piston-like plug 26 fitted into the bottom of the cylinder, its position being adjusted by a threaded adjusting screw 27 axially engaged through an end cap 30 or extension secured to the cylinder. Preferably, a bellows 28 ensures against escape of gas through the extension 30 or screw 27. The volume of the chamber 13 can be varied continually during operation. Any gas which bleeds through the clearance space between the cylinder and the plug 26 is returned to the exhaust gas gallery 24 through a line 29.

In order to reduce as much as possible alternating heat exchange between the working gas and the surfaces of the piston and cylinder in the vicinity of the expansion chamber, the piston bottom and cylinder bottom are preferably covered with a layer of heat insulating material.

Although primarily developed and best suited for use with cryogenic apparatus, the invention is likewise applicable to machines and apparatus where a piston is required to reciprocate in a cylinder and oil lubrication cannot be used.

What it is desired to secure by Letters Patent of the United States is:

1. In a machine which includes a piston reciprocating in a cylinder, and in which a gas under high pressure flows through the clearance space between the piston and the inner surface of the cylinder; means for effecting a self-centering action of the piston to maintain the same concentric with the cylinder without contact with the cylinder walls during reciprocation, comprising a plurality of annular grooves formed in one of the piston and cylinder surfaces, axially spaced along the length thereof, the intervening clearance space defined by the piston and cylinder surfaces between adjacent grooves varying axially in radial dimension.

2. The structure as claimed in claim 1 in which the distance between grooves is between $\frac{1}{20}$ and $\frac{1}{100}$ of the piston circumference.

3. The structure as claimed in claim 1 in which said radial dimension decreased axially in the direction of gas flow, at least over a part of the length of the piston.

4. The structure as claimed in claim 1 in which the radial dimension is greater between grooves than adjacent to the grooves.

5. The structure as claimed in claim 1 in which the grooves are in the piston.

6. The structure as claimed in claim 1 in which the grooves are in the piston, the radial dimension is greater between grooves than adjacent to the grooves, and in which the profile of the piston surface is symmetrical about a line midway between adjacent grooves.

7. The structure as claimed in claim 2 in which the grooves are in the piston and the radial dimension is greater between grooves than adjacent to the grooves.

8. A reciprocating piston machine having a cylinder and a piston moving relative one another, inlet and exhaust means for admitting gas into the cylinder to expand

for driving the piston in one direction, said inlet and exhaust means being located along the length of stroke of the piston to always provide a differential gas pressure along a portion of the cylinder occupied by the piston, a clearance space between the piston and cylinder comprised of a plurality of annular grooves formed between the piston and cylinder separated by radial dimension clearances axially varying of such construction to cause a self-centering action of the piston during reciprocation.

9. A machine as claimed in claim 8 in which the grooves are in at least a portion of the length of the piston, are separated by a distance which is substantially less than the circumference of the piston, and in which the radial clearance dimension between grooves varies along the axial length of the piston.

10. A machine as claimed in claim 9 in which the radial clearance dimension is greater between the grooves than adjacent the grooves.

11. A machine as claimed in claim 8 in which the inlet and outlet means include pasageways opening to the inside of the cylinder, a cooperating annular groove in the piston adapted during reciprocation to cover and uncover the first mentioned pasageways and passage means through the interior of the piston from said annular groove to the piston end.

12. A machine as claimed in claim 8 in which there is an expansion chamber in one end of the cylinder, the inlet means is adapted to have said gas enter under pressure and leave in expanded condition, and in which the inlet and exhaust means are formed by recesses circumferentially disposed about the cylinder and opening to the bearing surface thereof.

13. A machine as claimed in claim 12 in which the piston has a bore connecting with an annular groove therein, and located relative to said recesses to admit gas during a short portion of the stroke in the vicinity of lower dead center of the piston, and release the expanded gas from the bottom of the piston when the end uncovers the exhaust means in the vicinity of the lower dead center of the piston.

14. A machine as claimed in claim 12 in which the expansion chamber is adjustable in volume.

15. A piston type cryogenic device which comprises a cylinder having a cylindrical chamber therein, a piston arranged to reciprocate in the chamber and convert the heat from expanding gas into work while cooling the gas, a link connected with the piston and extending out of the cylinder adapted to have a work absorbing apparatus coupled therewith, a plurality of grooves spaced along the length of at least a portion of the piston, the diameter of the piston being such relative to the diameter of the chamber to provide a clearance space of very small dimensions, the piston having a profile between grooves to produce a radial dimension of the clearance space which varies in an axial direction, and said radial dimension being substantially greater between grooves than adjacent at least one of the grooves, the grooves being spaced axially by a dimension which is between $\frac{1}{20}$ and $\frac{1}{100}$ the piston circumference, inlet and exhaust means for gas to be admitted into said cylinder at high pressure and exhausted after cooling, the piston stroke, dimensions of the chamber and the pressures being chosen

so that there is always a differential pressure along the length of the piston whereby to cause the flow of some gas in the clearance space to make the piston self-centering in the cylinder.

- 5 16. A piston type cryogenic device which comprises a cylinder having a cylindrical chamber therein, a piston arranged to reciprocate in the chamber and convert the heat from expanding gas into work while cooling the gas, a link connected with the piston and extending out of the cylinder adapted to have a work absorbing apparatus coupled therewith, a plurality of grooves spaced along the length of at least a portion of the piston, the diameter of the piston being such relative to the diameter of the chamber to provide a clearance space of very small dimensions, 10 15 the piston having a profile between grooves to produce a radial dimension of the clearance space which varies in an axial direction, and said radial dimension being substantially greater between grooves than adjacent at least one of the grooves, the cylinder having first passage 20 means formed therein opening to said chamber to permit the introduction of gas at a relatively high pressure into the chamber while the piston is at approximately one end of its stroke, the expansion of the gas adapted to drive the piston in the opposite direction, with the piston 25 having valving means for cutting off the first passage means shortly after the piston commences to move in said opposite direction, the cylinder having second passage means opening to said chamber and normally closed off until the piston is approximately at the second end of the 30 stroke, and the said piston valving means acting also to uncover said second passage means to enable the exhaust of expanded and cooled gas from the chamber, said chamber having dimensions chosen with respect to said stroke to provide gas pressure in said chamber at all times whereby to cause gas always to be flowing in said clearance space, the piston being self-centering because of said 35 gas flow and piston profile.

- 40 17. A device as claimed in claim 16 in which said valving means of the piston comprise an annular recess in the piston, a central bore in the piston connecting with said recess and the piston end and said piston end, the latter serving to uncover said second passegeway.

- 45 18. A device as claimed in claim 16 in which the piston is hollow whereby cooling gas may pass through the same during reciprocation so that the temperatures of piston and cylinder change substantially together during operation of said device.
